(57) CLAIM

The ornamental design for a tabletop condiment holder, as shown and described.

DESCRIPTION

FIG. 1 is a front view in elevation of a tabletop condiment holder showing my new design;

FIG. 2 is a back view in elevation of the holder shown in FIG. 1;

FIG. 3 is a side elevational view thereof;

FIG. 4 is a side elevation view thereof opposite to that of FIG. 3;

FIG. 5 is a top plan view thereof;

FIG. 6 is a bottom plan view thereof; and,

FIG. 7 is a side perspective view thereof.
